US0D1048103S

(12) **United States Design Patent** (10) **Patent No.:** **US D1,048,103 S**
(45) **Date of Patent:** **** Oct. 22, 2024**

(54) **AIR INTAKE TOWER**

(71) Applicant: **Deere & Company**, Moline, IL (US)

(72) Inventors: **Timothy L. Ketterhagen**, Cedar Falls, IA (US); **Benjamin J. Schlesser**, Independence, IA (US); **Noah F. Homan**, Waterloo, IA (US)

(73) Assignee: **DEERE & COMPANY**, Moline, IL (US)

(**) Term: **15 Years**

(21) Appl. No.: **29/878,137**

(22) Filed: **Jun. 16, 2023**

Related U.S. Application Data

(62) Division of application No. 29/842,870, filed on Jun. 16, 2022, now Pat. No. Des. 993,992, which is a division of application No. 29/709,664, filed on Oct. 16, 2019, now Pat. No. Des. 967,199.

(57) **CLAIM**

The ornamental design for an air intake tower, as shown and described.

DESCRIPTION

FIG. 1 is a perspective view of an air intake tower according to our new design;

FIG. 2 is a front elevational view thereof;

FIG. 3 is a rear elevational view thereof;

FIG. 4 is a first side elevational view thereof;

FIG. 5 is a second side elevational view thereof;

FIG. 6 is a first plan view thereof;

FIG. 7 is a second plan view thereof;

FIG. 8 is a perspective view of another embodiment of an air intake tower according to our new design;

FIG. 9 is a front elevational view thereof;

FIG. 10 is a rear elevational view thereof;

FIG. 11 is a first side elevational view thereof;

FIG. 12 is a second side elevational view thereof;

FIG. 13 is a first plan view thereof; and,

FIG. 14 is a second plan view thereof.

The dash lines depict environment subject matter that forms no part of the claimed design. The dot-dash lines depict unclaimed boundary lines.

1 Claim, 10 Drawing Sheets
